(57) CLAIM

The ornamental design for a sports utility vehicle ("SUV") tent screen room, as shown and described.

DESCRIPTION

FIG. 1 is a perspective view of a sports utility vehicle ("SUV") tent screen room illustrating the present design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a perspective view of the sports utility vehicle ("SUV") tent screen room.

In the FIG. 7 drawing the broken lines depict a sport utility vehicle and a sports utility vehicle tent and form no part of the claimed design.
